CLAIM

The ornamental design for a charging case with earbuds, substantially as shown and described.

DESCRIPTION

FIG. 1 is a perspective view of a charging case with earbuds as seen from the front, top, and left side;

FIG. 2 is a top view thereof;

FIG. 3 is a front view thereof;

FIG. 4 is a bottom view thereof;

FIG. 5 is a back view thereof;

FIG. 6 is a right side view thereof; and,

FIG. 7 is a left side view thereof.

The broken lines illustrate portions of the charging case with earbuds and form no part of the claimed design.
